UNITED STATES PATENT OFFICE.

MAX W. ZABEL, OF CHICAGO, ILLINOIS.

RAILWAY SIGNALING APPARATUS.

No. 892,204.

Specification of Letters Patent. Patented June 30, 1908.

Application filed April 13, 1907. Serial No. 368,026.

To all whom it may concern:

Be it known that I, MAX W. ZABEL, a citizen of the United States, residing at Chicago, in the county of Cook and State of Illinois, have invented a certain new and useful Improvement in Railway Signaling Apparatus, of which the following is a full, clear, concise, and exact description, reference being had to the accompanying drawings, forming a part of this specification.

My invention relates to railway signaling apparatus and has for its object the provision of improved signals so that the entire right-of-way of a railroad is directly under the control of the despatcher.

A railway system is usually divided into train despatchers' sections which may be about one hundred miles long and one despatcher has charge of the routing of trains in said division. I provide a system wherein signals are to be placed along the right-of-way of said despatcher's section, and means to operate any one of said signals without operating the other, thus permitting the train despatcher to set a danger signal anywhere along his right-of-way, and prevent trains from entering a supposed dangerous zone along his section.

I will explain my invention more in detail by reference to the accompanying drawings forming part of this application in which

Figure 1 is a general view outlining my system; Fig. 2 is a detailed view of the sub-station apparatus as employed in one of the blocks of said right of way; and Fig. 3 is a diagrammatic view of the central station operating mechanism.

Like characters of reference indicate like parts throughout the different figures.

Referring more particularly to Fig. 1, I have shown a system of signals which I distribute along the right-of-way of a railroad track, the railroad track being graphically represented by the rails 1 and 2. I have shown the right-of-way divided into eight blocks respectively *a b c d e f g* and *h*. Each block is controlled by a signal or set of signals which signal or set of signals is operated independently of the signal or set of signals in any one of the other blocks in this same section. A part of the operating mechanism at each sub-station comprises a relay 3 and another relay 4 which relays are both connected in parallel so that should one relay fail to operate the other can be depended upon to respond. I have found in practice that these

relays do operate successfully, but two are provided to overcome any liability there might be of failure to operate on the part of one of the relays. I am enabled thus to 60 operate duplicate signal operating devices by reason of my improved control of said signal operating devices from the central station which in this instance is in the train despatcher's office.

I have diagrammatically indicated at *i* the central station in Fig. 1. The central station is connected to the various sub-station signaling apparatuses by line wires *k* and *l*. I will first describe in detail the operation of one of 70 the signals and its associated mechanism by referring more particularly to Fig. 2. I have shown in this figure three target signals 5, 6 and 7 although a greater or lesser number of targets may be used in one block, which 75 block I have represented as shown by the rails 1 and 2 in this figure, which block may be considered to have an average length of about five miles. The number of targets provided in a given block would depend naturally on the natural obstructions to vision in said block. If there are many curves there should be many target signals a general plan to be adopted being that at any point along the right-of-way in the block, one of the signals 80 may be in sight of the train crew so that the train crew can at all times be signaled from the despatcher's office. As before stated all the signals in one block preferably 85 operate simultaneously.

Each target signal has a visual target 8 which is fastened by means of a suitable chain or otherwise to a rotatable armature 9 which rotatable armature when it is in its horizontal or operated position draws said 95 target 8 behind the bullseye 10 and displays a red or danger signal. When the armature 9 is in its normal position as shown in the illustration the signal shows "clear." To operate the armature 9 I provide suitable pole 100 pieces 11 which pole pieces are magnetized by suitable coils 12 when provided with current from the battery 13. I provide upon the chain 14 of the signal 6 a suitable contact lever 15 which engages a spring 16 and 105 when signal 6 is operated spring 16 is in closed circuit with spring 17. When the target 8 of the signal 6 is in its lower or clear position spring 16 engages spring 18 for purposes to be described hereinafter. The actuation of the signals in a block is primarily 110 accomplished when the relay 19 is actuated.

I will describe first how the actuation of the relay 19 effects this operation. Assume that one impulse is given by the relay 19 as would be the case if current flowed through said relay to the ground which current is to be furnished from the central station, then the local apparatus at this sub-station will operate as follows: Armature 20 is drawn up and current passes from the positive pole of battery 13 through contact spring 18, contact spring 16, armature 20, relay 21, through the operating coils 12 of the signals 5, 6 and 7, by means of the line wire 22, thence to line wire 23 and back to the negative pole of the battery 13 over local wire 24. Thus all of the armatures 9 rotate into their horizontal or danger position. This moves the contact 16 from engagement with spring 18 into engagement with spring 17 and current now passes from the positive pole of battery 13 through armature 25 through the relay 21 to the line wire 22 thus locking the battery current to the line wires 22 and 23 and thus holding the armatures 9 in a horizontal position. Now if a second impulse is sent over the relay 19 its armature 20 will again be attracted and this attraction of the armature 20 places a short circuit around the winding of the relay 21, thus allowing it to fall back and breaking the battery current from battery 13 to the line wire 22, so that all signals return to their normal position immediately the armatures 25 and 20 return to their normal position. Of course the armatures 9 are slow acting and therefore contact at spring 18 is not made for a short while, or at any rate not until the impulse through relay 19 has subsided. It will thus be seen that a momentary impulse of the relay 19 one of which is provided at each of the signals 6 throughout the section, one of which signals 6 is provided in each block, said signals 5, 6 and 7 in the particular block whose relay 19 is attracted will be set at danger and a second impulse of the relay 19 will restore the signals to their normal position. The eight relays 19 are selectively actuated as I will describe more in detail, that is, I am enabled by means of my improved system to operate the relay 19 in either one of the blocks from *a* to *h* without disturbing the corresponding relay 19 in either one of the other blocks, thus each block is independently under the control of the despatcher at the station *i*. As the two relays corresponding to the relays 3 and 4 in sub-station *a* operate simultaneously or at least are arranged for such operation, I will describe this selective operation of the relay 19 in connection with merely one of said relays 3. I have not indicated the relays 19 in the accompanying drawing of Fig. 1, but said relays are connected uniformly by the wire 26 through the winding of said relay 19 to ground as indicated more in detail in Fig. 2. Corresponding to the relay 3 of station *a*

there are similar relays 27, 28, 29, 30, 31, 32, 33 for the stations *b*, *c*, *d*, *e*, *f*, *g* and *h* respectively. Said relays are polarized so that they are responsive to positive battery current and negative battery current depending upon the direction of their winding. I make use of this feature in the operation of the system.

The system is arranged in order to get an eight station selective signaling system in such a manner that relays 3 and 30 are both connected between the line wire *k* and ground through the interposition of a suitable impedance coil 34. Both relays 3 and 30 operate when positive current is projected over the wire *k* to ground. Relays 28 and 32 are also connected between the same line wire *k* and ground and will operate when negative battery current is impressed on wire *k* to ground. Relays 27 and 31 are both connected between line wire *l* and ground, and operate when a positive current is impressed on line wire *l* to ground. Relays 29 and 33 are also connected between line wire *l* and ground and operate with negative battery current on said line wire *l* to ground. It will thus be seen that whenever positive or negative battery current is impressed on either line wires *k* or *l* that two relays operate, thus, depending upon the connection of the battery current, a selection of four blocks is already obtained. Now, however, when either group of two relays operates, the relay 19 at the various stations is connected selectively, so as to get a further selection of any particular one of said group of two. This is done, as I will explain in connection with stations *a* and *e*. For instance when the relays 3 and 30 operate they close the circuit through two relays 19, that is, a relay 19 at station *a* and a relay 19 at station *e*, but the relay 19 at station *a* is connected by said relay 3 between the line wire *l* to ground which is a different conductor from the one to which said relay 3 is connected, which is line conductor *k*, while in the case of station *e* the relay 19 is connected by said relay 30 between the line conductor *k* to ground.

Now to operate the particular relay 19 which it is desired to operate, that is, either the one at station *a* or the one at station *e*, I provide preferably an alternating current at the sending station *i*, which, when this battery current is connected as stated, can be connected either to the line wire *k* or the line wire *l* thus to operate either the relay 19 at station *a* or the relay 19 at station *e*, which said relay 19 only operates with alternating current and preferably not with direct current. Thus, to sum up this system any time battery current is projected over either wire *k* or *l* two relays operate, which relays close the circuit through a second relay, and the desired selection of either one of the second relays is obtained by having alternating cur-

rent either on line wire *k* or on line wire *l*. This same principle is carried out through the remaining stations, and thus a selective signal can be conveyed to one of eight blocks 5 depending upon the connection of the battery current and the suitable connection of the alternating current.

Condensers 35 are connected in series with relays 19 where they are on the same line 10 wire as their associated first relays to prevent passage through said relays 19 of battery current. It will be apparent that in the stations *e f g* and *h* they are operated when both battery current and alternating current 15 are simultaneously on the same line wire. Now when alternating current and direct, or in this case, continuous current are on the same line wire they combine to form a resultant current which is similar in many respects 20 to that obtained by rapidly making and breaking a battery current, and I prefer to operate these latter stations by this sort of combination, as I find it gives better results in practice. To cause the operation of these 25 various stations now we will refer more particularly to Fig. 3 which shows the apparatus needed at the central station *i*. The line wires *k* and *l* are passed through a selective key *m* which has eight spring combinations, which I have lettered respectively *an*, 30 *bn*, *cn* etc. so that spring combination *an* corresponds to block *a* and spring combination *bn* corresponds to block *b*, etc. I have shown a generator *o* as furnishing the alternating current, and two sets of batteries *p* and *q* grounded at *r*, that is the positive terminal or battery *p* and the negative terminal of battery *q* are permanently grounded. The 35 spring combinations *an*, *bn*, *cn*, and *dn* connect either positive or negative battery current to either the line wires *k* or *l*, and alternating current from the generator *o* to the opposite line wire, thus to select stations *a*, *b*, *c*, and *d* when either of their corresponding 40 spring combinations in the key *m* is operated.

I have shown an interrupter *s* which is capable of supplying the positive pulsating current or negative pulsating current from the batteries *p q*, and which by suitable 45 spring combinations *en*, *fn*, *gn* and *hn* connects either positive or negative pulsating current to either line wires *k* or *l*. Condensers *t* are shown to facilitate the operation of the interrupter. The battery *u* operates the interrupter relay *v*. It will thus be seen that by the use of my improved system practical means are provided whereby at the central station or despatcher's office *i* a series of buttons corresponding to eight 50 different spring combinations can be operated to selectively signal any one of eight different blocks, thus to constitute any block a danger zone if trains are not operating according to schedule or for other reasons.

55 My improved system permits duplication

of apparatus to prevent failures. As before stated the number of separate signals in each block will depend to a large extent, upon the condition of the right-of-way.

While I have herein shown and particularly described the preferred embodiment of my invention, I do not wish to limit myself to the precise construction and arrangement as herein shown and set forth. But

Having thus described my invention, I claim as new and desire to secure by Letters Patent:

1. In a railway signaling system a signal sending station, a plurality of signal controlling devices distributed along a railroad right-of-way, switching mechanism at the signal sending station and current supplying means for furnishing currents of different electrical character for selectively operating said signal controlling devices, signals under the control of said signal controlling devices and switching means whereby an operative impulse of the signal controlling device will manipulate the signal in one direction and a succeeding operative impulse will manipulate said signal in a different manner.

2. In a railway signaling system a signal sending station, a plurality of signal controlling devices distributed along a railroad right-of-way, switching mechanism at the signal sending station and current supplying means for furnishing currents of different electrical character to operate independently of each other said signal controlling devices, signals under the control of said signal controlling devices, and means whereby a signal when operated will simultaneously operate an additional signal.

3. In a railway signaling system a signal sending station, a plurality of signal controlling devices distributed along a railroad right-of-way, switching mechanism at the signal sending station and current supplying means for furnishing currents of different electrical character to operate independently of each other said signal controlling devices, a plurality of signals under the control of said signal controlling devices, and switching means whereby an operative impulse of the signal controlling device will give a certain indication by a plurality of signals, and a succeeding operative impulse will give a different indication by said last aforesaid signals.

4. A railway signaling system comprising a signal sending station, a plurality of signal controlling devices distributed along the right-of-way, means at the sending station for supplying current of different electrical character to operate said signal controlling devices independently of each other, and signals to guide in the operation of trains under the control of said signal controlling devices.

5. A railway signaling system comprising a signal sending station, a plurality of signal

controlling devices distributed along the right-of-way, means at the sending station for supplying currents of different electrical character to operate said signal controlling devices independently of each other, and a plurality of simultaneously operating signals each under the control of some or all of said signal operating devices.

6. In a railway signaling system a signal sending station, a plurality of signals to guide in the operation of trains distributed along the right-of-way, electro magnetic means for governing the operation of said signals, and means at the signal sending station comprising switch contacts and currents of different electrical character for operating the electro magnetic means independently of each other, to selectively operate the signals.

7. In a railway signaling system a signal sending station, a plurality of signals to guide in the operation of trains distributed along the right-of-way, electro magnetic means for governing the operation of said signals, relays forming part of said electro magnetic means, and means at the signal sending station comprising switch contacts and currents of different electrical character for selectively operating the electro magnetic means to selectively operate the signals.

8. In a railway signaling system a signal sending station, a plurality of signals to guide in the operation of trains distributed along the right-of-way, electro magnetic means for governing the operation of each of said signals, duplicate and simultaneously operating relays forming part of said electro magnetic means, and means at the signal sending station comprising switch contacts and currents of different electrical character for selectively operating the electro magnetic means to selectively operate the signals.

9. A railway signaling system comprising a central station and a railroad right-of-way divided into blocks, visual signals in said blocks, all of the signals in one of said blocks operating simultaneously, electro magnetic means for controlling the operation of said signals, and means comprising current supplying devices for furnishing currents of different electrical character at the signal sending station for operating the electro magnetic means independently of each other to selectively operate the signals.

10. In a selective signaling system for railways comprising a signal sending station, signal blocks into which said railroad right-of-way is divided, a signal provided in each of said blocks, electro magnetic devices for controlling the operation of said signals, means at the signal sending station for furnishing different characters of current, and switching means to operate said electro magnetic devices independently of each other.

11. In a selective signaling system for railways comprising a signal sending station,

signal blocks into which the railroad right-of-way is divided, a signal provided in each of said blocks, means whereby additional signals in the same block may be operated simultaneously with the operation of either of the aforesaid signals, electro magnetic devices for controlling the operation of said signals, means at the signal sending station for furnishing different characters of current, and switching means to operate said electro magnetic devices independently of each other.

12. A selective signaling system for railways comprising a signal sending station, signal blocks into which the railway right-of-way is divided, a master signal in each block, electro magnetic means for operating said master signal, switching devices a current supplying means for furnishing currents of different electrical character at the sending station for operating the electro magnetic devices independently of each other, and controlling devices associated with the aforesaid master signals whereby additional signals may be operated in unison with the master signal in the same block.

13. In a railway signaling system a signal sending station, a plurality of signals to guide in the operation of trains distributed along the right-of-way, electro magnetic means for governing the operation of said signals, and means at the signal sending station including current supplying devices for furnishing currents of different electrical character, to operate independently of each other the electro magnetic means thereby to cause a selective operation of the said signals.

14. In a railway signaling system a signal sending station, a plurality of signals to guide in the operation of trains distributed along the right-of-way, an electro magnetic device for each signal to govern its operation, and operating means at the signal sending station comprising current supplying means for furnishing currents of different electrical character to operate selectively the desired electro magnetic device, thus to selectively operate the signals.

15. In a railway signaling system a signal sending station, a plurality of signal controlling devices distributed along a right-of-way, switching mechanism at the signal sending station, a current supplying device for generating currents of different electrical character for selectively operating a desired signal controlling device, signals under the control of said signal controlling devices, and switching means whereby an operative impulse of the signal controlling device will manipulate the signal in one direction, and a succeeding operative impulse will manipulate said signal in a different manner.

16. In a railway signaling system a signal sending station, a plurality of signals to guide in the operation of trains distributed along the right-of-way, a relay for each signal to

govern its operation, and manually operated switching instrumentalities controlling current supplying devices for furnishing currents of different electrical character to selectively 5 operate any desired relay, thereby to selectively operate the signals.

17. In a railway signaling system a signal sending station, a plurality of signals to guide in the operation of trains distributed 10 along the right-of-way, a relay for each signal to govern its operation, a local power supply to operate the signal when operative impulses of said relay are effected, and manually operated switching instrumentalities 15 including current supplying devices for furnishing currents of different electrical character to selectively operate any desired relay, thereby to selectively operate the signals.

18. In a railway signaling system, a signal 20 sending station, a plurality of signals to guide in the operation of trains distributed along the right-of-way, a signal controlling device for each signal to govern its operation, and instrumentalities including current sup- 25 plying devices for furnishing currents of different electrical character to electrically operate said signal controlling devices independently of each other to selectively set and release said signals.

19. In a railway signaling system, a signal 30 sending station, a plurality of signals to guide in the operation of trains distributed along the right-of-way, a signal controlling device for each signal to govern its operation, local power supplying apparatus to operate 35 said signals, and instrumentalities including current supplying devices for furnishing currents of different electrical character to selectively operate said signal controlling devices independently of each other to select- 40 ively set and release said signals.

20. A railway signaling system comprising a signal sending station, a plurality of signal controlling devices distributed along the right-of-way, switching means at the sending 45 station for controlling the supply of currents of different electrical character to operate said signal controlling devices independently of each other, whereby to set or restore any desired signal, and signals to guide in the 50 operation of trains under the control of said signal controlling devices.

In witness whereof, I hereunto subscribe my name this sixth day of April, A. D. 1907.

MAX W. ZABEL.
